Amos Paul of South Newmarket, N.H.

Letters Patent No 474 Dated July 20th 1852

The schedule referred to in these Letters Patent and making part of the same

To all to whom these presents shall come:

Be it known that I, Amos Paul of South Newmarket in the County of Rockingham & State of New Hampshire, have produced a new and original design for the top, bottom & side plates of a parlor stove, and I hereby declare that the said new design is fully described and represented in the following specification and accompanying drawings to which reference is hereinafter made.

The figures of the accompanying plates of drawings represent my new design. In Plate 1, fig. 1 is a plan or top view of the top plate. Fig. 2 is a vertical section of the same taken in the plane of the line A.B, fig. 1. Fig. 3 is an elevation of the bottom plate. In Plate 2, fig. 4, is an elevation of the side plate and fig. 5 is a section of the same taken in the plane of the line B.C, fig. 4.

The top plate is ornamented with the mouldings a a - b b of the shape shown in fig. 1. The top of the plate has on it two panels c e - e c with raised vine work d d - d d, the centre of the plate being ornamented with circular mouldings e e, with small raised points f f & g g.

The bottom plate has around its edge the mouldings q, q, q, the base z. z. of the stove having cast on it large raised points f, f.

The side plate is ornamented at the top with the points f f and on the sides with mouldings i i & c. In the centre of the plate is the six pointed leaf k, k, enclosed by circular mouldings z, z, between which and the mouldings m, m, is the vine work o o. In each corner of the plate is the leaf work p, p.

Having thus described my new design I shall state my claim as follows:

What I claim as my production and desire to have secured to me by Letter Patent, is the new design consisting of the mouldings, raised points, vine and leaf work, herein above described and represented in the drawings, for the top, bottom, and side plates of a parlor stove.
